UNITED STATES PATENT OFFICE.

WILLIAM H. SIPPEL, OF INDIANAPOLIS, INDIANA.

SPARK-PLUG.

1,320,803.

Specification of Letters Patent.

Patented Nov. 4, 1919.

Application filed November 11, 1918. Serial No. 281,980.

To all whom it may concern:

Be it known that I, WILLIAM H. SIPPEL, a citizen of the United States, and a resident of Indianapolis, county of Marion, and State of Indiana, have invented a certain new and useful Spark-Plug; and I do hereby declare that the following is a full, clear, and exact description thereof, reference being had to the accompanying drawings, in which like letters refer to like parts.

In small gas engines the principal trouble with spark plugs is due to the accumulation of soot and carbon and fouling of the gap or gaps thereby and causing short circuiting.

In high compression internal combustion engines the principal difficulty is due to the mechanical breakdown of the material composing the spark plugs on account of the extreme heat caused by the powerful explosions therein. In the ordinary automobile internal combustion engine, the heat within the cylinder is about 500 or 600 degrees temperature, while in an airplane high compression engine, the heat reaches about 1500 or 1600 degrees. With such variance in heat conditions, the functioning of the spark plugs in the two classes of engines is quite different.

Owing to enormous heat in the high compression class of engines, the central electrode and porcelain stem are injured. With the present type of spark plugs, the central electrode is either cemented in place or fits tightly and the result is that the steel electrode expands relatively more than the porcelain stem so as to burst the porcelain stem or crack it and thus render the plug worthless. Also in the present type of plugs one end of the porcelain stem extends into the open air and the other into communication with the cylinder chamber. The inner end becomes excessively heated with high compression engines, while the outer end in the atmosphere is of a relatively low temperature, and the difference in the temperature of the two ends of the porcelain stem also causes it to break down and crack.

The chief feature of this invention, whereby the difficulties of the present type of spark plugs are overcome for use in high compression types of engines, is mounting the porcelain stem so that it will be subject only to the temperature of the cylinder and not project into the atmosphere and be affected thereby, and also in mounting the

porcelain stem so that it is spaced and, therefore, insulated from the body of the plug so that its temperature will be uniform throughout its length. Another feature of the invention consists in mounting the steel electrode so that it will be held only at its outlet end, and will extend loosely through the porcelain stem, so that there will be a space between the electrode and porcelain stem whereby the electrode will not tend to heat the interior of the porcelain stem to a greater temperature than the exterior and thus cause breaking or cracking of the porcelain stem. Another feature of the invention is in so constructing and mounting the porcelain stem that it can be readily removed and renewed when desired.

Still another feature of the invention is the simplicity of its construction.

The full nature of the invention will be understood from the accompanying drawings and the following description and claims.

In the drawings, Figure 1 is an elevation of the spark plug. Fig. 2 is a central vertical section therethrough. Fig. 3 is a transverse section on the line 3—3 of Fig. 2.

In this plug there is a body 10 of the usual type excepting the inner chamber 11 thereof extends rather deeply into the bottom of the spark plug and the outer end of the spark plug is chambered so as to leave a thin annular wall 12 which can be spun on a fiber head 13. This fiber head has a peripheral groove into which the outer end of the portion 12 of the spark plug is contracted whereby the parts are secured together.

The porcelain stem 15 is tubular and extends through the internal bore 16 of the outer portion of the body of the spark plug loosely. The bore of the plug body is appreciably greater than the external diameter of the porcelain stem so that the porcelain stem will not be materially affected by the temperature of the body of the spark plug or be in contact therewith. The upper end of the porcelain stem is held in place by the fiber head 13 in which it fits snugly. This fiber head is made of any material which is a poor conductor of heat and, therefore, is not much influenced by the heat of the spark plug and protects the porcelain stem therefrom. It also protects the outer end of the porcelain stem from the atmosphere entirely.

There is a short electrode 20 secured to

the inner portion of the body 10 of the plug and near it a long steel central electrode 21 which extends loosely through the porcelain stem so as to be entirely out of contact there-
5 with and so that there will be air between the two for insulating the porcelain stem from the electrode.

Obviously the porcelain stem will obtain its heat from the heated air within it and 10 surrounding it and it will, therefore, have a uniform temperature throughout its length so that it will not be caused to break down or crack by different degrees of expansion and contraction of different portions thereof, 15 under the influence of the heating and cooling of the spark plug or the central electrode.

The central electrode extends through the bore in the stem 15 and through the fiber 20 head and is held in place by means of a lock washer 24 and a lock nut 22, the lower portion of the electrode 21 having a cap 25 thereon which engages the inner end of the stem 15 and binds the stem between the cap 25 and the fiber head 13. The lock washer 24 also allows for contraction and expansion due to heat variance. A knob 23 is threaded onto the upper end of the electrode 21 and over the lock nut 22 and is held in position by means of a lock washer 27 between the knob and lock nut. The knob 23 serves as a binding post at the upper end of the spark plug.

From the foregoing it is apparent that 35 there is no part of the porcelain stem extending above the plug body where it could accidentally be broken by a wrench or tool, nor is there any portion of it exposed to the atmosphere, thus distinguishing it from the 40 present spark plug, wherein about half of the porcelain stem extends into the atmosphere so that the two ends of the porcelain stem are subjected to two very different temperatures. The porcelain stem can ex- 45 pand within the valve stem without con-

tacting with it and thus without becoming broken and likewise the central electrode can expand within the porcelain stem without engaging and breaking it.

The plug is made of so few parts that it 50 is very simple and also of very light weight which is a factor in air-plane service. By removing the knob 23 and lock nut 22, the electrode 21 and stem 15 may be easily re- 55 moved from the spark plug body and renewed when desired.

The invention claimed is:

1. A spark plug including a central electrode, an insulating stem surrounding the same, a plug body with a large chamber 60 surrounding the inner and major portion of the insulating stem and with the outer portion of the chamber contracted, and insulating means which is a poor conductor of heat secured to the outer end of the plug body for 65 supporting the outer end of the insulating stem so that the remaining portion thereof will be free.

2. A spark plug including a central electrode, an insulating stem surrounding the 70 same, a plug body surrounding the insulating stem with a central chamber therein with its inner and major portion considerably larger therethrough and an outer contracted portion spaced from the stem. 75

3. A spark plug including a central electrode, an insulating stem surrounding the same, a plug body surrounding the insulating stem and spaced entirely therefrom and its outer end being chambered to form a thin 80 wall, and insulating means which is a poor conductor of heat secured in the chambered end of the plug body by the thin wall of the latter being spun thereon and said insulating means secured to and supporting the outer 85 end of the insulating stem.

In witness whereof I have hereunto affixed my signature.

WILLIAM H. SIPPET.
